(57) **CLAIM**

The ornamental design for a batch pathological specimen scanner, as shown and described.

DESCRIPTION

FIG. 1 is a front view showing a batch pathological specimen scanner;

FIG. 2 is a rear view of the batch pathological specimen scanner in FIG. 1;

FIG. 3 is a left side view of the batch pathological specimen scanner in FIG. 1, a right side view thereof is symmetric to the left side view and is omitted;

FIG. 4 is a top view of the batch pathological specimen scanner in FIG. 1;

FIG. 5 is a bottom view of the batch pathological specimen scanner in FIG. 1;

FIG. 6 is a front, left side and top perspective view of the batch pathological specimen scanner in FIG. 1;

FIG. 7 is a rear, right side and top perspective view of the batch pathological specimen scanner in FIG. 1;

FIG. 8 is a reference view showing the state in use of the batch pathological specimen scanner in FIG. 1; and,

FIG. 9 is another reference view showing the state in use of the batch pathological specimen scanner in FIG. 1.

The broken lines depicting the specimen plates in FIGS. 8 and 9 represent environmental subject matter and form no part of the claimed design.

1 Claim, 9 Drawing Sheets
